UNITED STATES PATENT OFFICE.

ALEXANDER CARSTENS AND JAMES H. HENLEY, OF LEADVILLE,
COLORADO.

SAFETY APPARATUS FOR SETTING CAGE-CHAIRS IN MINING-SHAFTS.

SPECIFICATION forming part of Letters Patent No. 677,437, dated July 2, 1901.

Application filed September 27, 1900. Serial No. 31,320. (No model.)

To all whom it may concern:

Be it known that we, ALEXANDER CARSTENS and JAMES H. HENLEY, citizens of the United States, residing at Leadville, in the county of 5 Lake and State of Colorado, have invented a new and useful Safety Apparatus for Setting Cage-Chairs in Mining-Shafts, of which the following is a specification.

Our invention relates to an improvement 10 in safety apparatus for setting cage-chairs in mining-shafts, the object of our invention being to effect improvements whereby the cage-chairs at the various levels may be operated by the engineer stationed at the hoisting-engine, whereby danger of accidents arising 15 from misplaced cage-chairs is avoided.

Heretofore the cage-chairs which support the cages in the mining-shafts at various levels have been set by persons called "cagers" 20 stationed at the said levels, the setting of the cage-chairs being entirely out of the control of the engineer who operates the hoisting-engine. This mode of setting the cage-chairs is exceedingly dangerous, and it frequently 25 happens that disastrous accidents result from the misplacing of the cage-chairs.

The object of our invention, as hereinbefore indicated, is to provide means whereby the cage-chairs in a mining-shaft at the various 30 levels may be set by the engineer who operates the hoisting-engine in order to arrest the descent of a cage and support the same at any desired level.

To this end our invention consists in the 35 combination of cage-chairs, setting devices therefor, and an operating connecting element, as a cord, cable, rod, or the like, between said setting devices, whereby the same may be operated from a point distant from 40 said cage-chairs.

Our invention further consists in the combination of cage-chairs, a rock-shaft, connections between the latter and the cage-chairs whereby motion is communicated from said 45 rock-shaft to said cage-chairs, a setting-lever on said rock-shaft, and an operating element, as a cord or the like, connected to said setting-lever.

Our invention further consists in the peculiar construction and combination of de-

vices hereinafter fully set forth, and pointed out in the claims.

In the accompanying drawings, Figure 1 is a section of a mining-shaft provided with our improved safety apparatus for setting the 55 cage-chairs therein. Fig. 2 is a detail sectional view of a fluid-pressure apparatus for operating the connecting cord or cable which controls the cage-setting devices. Fig. 3 is a detail elevation, partly in section, of a portion 60 of the framing in a mining-shaft provided with our improved setting devices for the cage-chairs. Fig. 4 is an elevation of the same at right angles to Fig. 3. Fig. 5 is a horizontal sectional view of the same. 65

The cage-chairs 1 on opposite sides of the shaft 2 at each level in the mine are connected by means of rods 3 to arms 4 on a rock-shaft 5, which has its bearings, as at 6, on one side of the timber frame in which the cage 7 is hoisted and guided. A setting-lever 8 is adapted to operate the rock-shaft, and in the form of our invention herein shown said setting-lever is formed integrally with one of the arms 4 on the rock-shaft. The setting-lever 75 is disposed to one side of the shaft out of the way of the cage. It will be observed by reference to Fig. 3 that the setting-lever and the connections between the same and the chairs normally dispose the latter out of the way of 80 the cage, so that normally the chairs at the various levels in the shaft are out of the way of the cage, and the latter may be raised or lowered from the hoisting-engine, which is indicated at A, Fig. 1, and is of the usual 85 construction or may be of any suitable construction, B representing the hoisting-cable attached to the cage, and C representing the direction-sheave above the mouth of the shaft, over which the said hoisting-cable passes. 90

In connection with the setting-levers at the various levels in the shaft we employ a connecting, controlling, or operating element—such as a cord, cable, or rod 9—which passes through openings 10 in said setting-levers or 95 is otherwise appropriately connected thereto and connects said setting-levers, so that the latter may be operated in unison, and said element is provided with stops 11, said stops and levers coacting to raise the levers with 100

the said connecting element, and the latter passes over a direction-sheave 12 and terminates at a suitable point. Preferably the connecting or controlling element terminates at 5 the hoisting-engine, where it may be conveniently operated by the engineer in charge of the hoisting-engine, and hence the chair-setting devices are controlled and operated from a point distant from the levels at which they 10 are situated, and the engineer when lowering or hoisting a cage by setting the chairs may cause the same to support the cage at any desired level.

The chairs being normally out of the way 15 of the cage, so that the latter is free to be raised or lowered, and the cage-chairs being controlled and operated by the engineer at the hoisting-engine, all danger arising from misplaced cage-chairs is obviated, as will be 20 readily understood.

Any suitable means may be employed for operating the controlling and connecting element. In Figs. 1 and 2 of the drawings we illustrate a suitable fluid-pressure mechanism 25 D, which comprises, essentially, a cylinder a, a piston b therein, a valve c to admit steam or other fluid under pressure to said cylinder and exhaust the same therefrom,

and a piston-rod d, the head e thereof being adapted for the attachment thereto of the operating or controlling connecting element. 30

Having thus described our invention, we claim—

1. The combination of a cage and a hoisting-engine therefor, cage-chairs at various 35 levels to support said cage, setting devices for said cage-chairs, and an operating element, as a cord or the like, connected to said setting devices and extending to a point near said hoisting-engine, for the purpose set forth, 40 substantially as described.

2. The combination of a cage and means to raise and lower the same, a series of cage-chairs at various levels to support said cage, each of said cage-chairs having a setting-lever, an operating-cord, connected to the said 45 setting-levers, and means to actuate said cord, substantially as described.

In testimony that we claim the foregoing as our own we have hereto affixed our signatures 50 in the presence of two witnesses.

ALEXANDER CARSTENS.
JAMES H. HENLEY.
